UNITED STATES PATENT OFFICE.

HECTOR OSMOND RIVERS, OF ESSENDON, NEAR MELBOURNE, VICTORIA, AUSTRALIA.

DOOR LOCK.

Application filed October 11, 1922, Serial No. 593,857, and in Australia December 1, 1921.

This invention relates to an improved door lock and has been devised in order to provide a latch which defies the lock picker and which is preferably combined with a locking bar or bolts to further reduce the risk of unauthorized entry into shops or dwelling houses.

The essential characteristics embodied in this invention consist in means whereby the lock mechanism may be interrupted at will so that a skeleton or like illegal key cannot operate in such a way that the lock responds thereto, thus causing the door to which the lock is fitted to open.

15 The lock is also characterized in that the key, on insertion, does not require turning, the fact of inserting the key, once the mechanism is in a condition to receive same, to cause all the lock mechanism to harmonize 20 and be capable of operation.

A further essential characteristic of this invention is that once the lock mechanism is interrupted a key cannot enter the keyway for the reasons to be hereinafter described.

25 A further essential feature which characterizes this invention is that when the door is locked the operating handle of the lock moves freely and does not function until such time as the key is inserted in the key- 30 way, and when the various mechanisms are in a condition to receive the key and respond to its insertion.

But to more readily understand this invention it will now be described with reference to the accompanying drawing in which:—

Figure 1 is a front elevation of a lock constructed according to this invention.

Figure 2 is a side elevation thereof.

40 Figure 3 is a rear elevation thereof.

Figure 4 is a side elevation of an internal pin barrel.

Figure 5 is a transverse section thereof.

Figure 6 is a plan view of the pin controlling bar.

Figure 7 is a central sectional elevation thereof.

Figure 8 is a central sectional elevation of a modification of Figures 6 and 7.

50 Figure 9 are views in plan and side elevation of an extension piece.

Figure 10 is a central sectional elevation of the lock illustrated in Figures 1, 2, and 3.

55 Figure 11 is a transverse sectional elevation thereof.

According to this invention, the body 1

of the lock is preferably formed of brass or gun metal and is preferably circular in shape with a rim or flange 2 at the front which seats on the outer surface of the door 60 while the body 1 enters a hole suitably shaped in the door and extends to a sufficient depth approximately the thickness of the door.

If a particular door is above average 65 thickness, extension pieces 1^a are used adapted to fit on the squared end 1^b of member 5.

This body member 1 is bored preferably at the top to receive an outwardly projecting spindle 3 fitted externally of the door 70 with a suitable handle 4.

The spindle 3 is fitted within a barrel or sleeve 5 and projected to the front of the door and the barrel 5 meets the rear surface of the body member 1 which is bored or 75 cast with a hole sufficient to allow of the reception of the sleeve or barrel 5.

The sleeve or barrel 5 is provided with a plurality of holes 6 and a central hole 7 adapted to receive the portion 8 of the spindle 80 3.

The portion 8 is formed with a slot 9 adapted to receive a resilient filling consisting of upper and lower plates 10—10^a and springs 11 or alternatively the springs 85 11 may support independent plates 12 each plate corresponding with the number of locking pins used.

The barrel 5 is held within the body 1 of the lock by means of a screw 13 which passes 90 through said body and into an annular groove 14 formed on the barrel 5.

The spindle 3 is formed with a flat 15^a adapted to receive the operating handle 4 which is kept in position by means of a 95 screw 16^a the shank of which passes into the end of the spindle 3.

The section illustrated in Figure 10 shows the lock in open position with the locking pins 15 uppermost.

100 This open or unlocked position is obtained by inserting the key in the keyway 16 which lifts the lower lifting pins 17 sufficiently to cause the locking pins to rise clear from the holes 18 in which the lifting pins 17 are seated.

On then turning the handle 4 the barrel 5 moves also which carries the pins 15 to lock the door the barrel 5 is turned which brings the pins 15 and 17 together as shown 110 in Figure 11 when the barrel 5 is held from further rotation until the key is again in-

serted the handle 4, 3, 8 turning freely and hence ineffectively in retractor barrel 5.

In the position as shown in Figure 11, although the barrel 5 is locked, the bar 8 is free to rotate which is done in order to interrupt the mechanism and bring the solid surface 18^a of the bar 8 against the locking pins 15 which prevents the insertion of a key to operate the lock.

10 In operating the lock the handle 4 is moved to the position shown in Figures 1 and 2 which brings the resilient slotway of the bar 8 into line with the locking pins 15 which enables the key to operate and lift 15 the lower lifting pins 17 and locking pins 15, the locking pins 15 moving into the slotway 9 sufficiently to carry said pins 15 clear of the holes 18 in which the lifting pins 17 are seated, the key being then withdrawn. 20 In carrying the lock into operation and in order to lock a door thereby, the barrel 5 is rotated by means of the handle 4, thus bringing the pins 15 and 17 together as shown, when the barrel 5 is held from further rotation until the key is again inserted, incidentally the bar 8 is free to rotate and thus interrupt the lock mechanism and bring the solid surface 18^a of the bar 8 against the locking pins 18 which prevents the insertion 30 of a key to operate the lock.

What I claim as my invention and desire to secure by Letters Patent is:

1. A lock comprising, a body, a sleeve housed in the body, a bar housed in the 35 sleeve, a handle on the bar, a slot in the bar, plates positioned in the slot, and springs cooperating with the plates to press them outwardly toward the periphery of the bar.

2. A lock according to claim 1, said sleeve

having a plurality of apertures, and a groove 40 adapted to receive attaching means carried by the body.

3. A lock comprising a hollow body, a flange thereon, a sleeve positioned in the body, a bar received by the sleeve, pin receiving apertures in the sleeve, locking pins in the sleeve apertures, a slot biased outwardly in the bar, spring controlled plates in the slot, apertures in the body, said plates pushing said locking pins across the joint 50 between said sleeve and body when said pins come into registry with said body apertures, lifting pins in the body apertures for pushing said locking pins within the peripheral bounds of said sleeve when engaged by a 55 suitable key, a keyway in the body opening into the body apertures, a screw and groove connection between the body and the sleeve, and an operating handle on the bar.

4. In a lock, means for preventing unauthorized use, comprising, a lock body, lifting pins in the body, a sleeve turnable in the body, a bar turnable at times in the sleeve, locking pins in the sleeve operable to prevent relative rotation of the sleeve and bar, rotation of the barrel resulting in engagement of the locking pins with the lifting pins.

5. A lock comprising, a body, a slotted bar therein, a plurality of spring controlled plates in the slot, a sleeve receiving the bar, and locking pins corresponding in number to, and cooperating with, the spring controlled plates and normally biased outwardly by said plates.

Signed at Melbourne, Victoria, Australia, this 31st day of August, A. D. 1922.

HECTOR OSMOND RIVERS.
